ELECTRIC SWITCH

Hermann Nabakowski, Berlin, Germany

Application July 3, 1936, Serial No. 88,847
In Germany July 4, 1935

5 Claims. (CL 200—167)

This invention relates to tumbler switches for electric circuits and provides for a switch of the kind which indicates its affixed location by means of a glowing lamp, especially an incandescent lamp, fitted in the lamp-holder and which glows when the switch is switched off.

The arrangement of lamps in switches and particularly that of glow lamps, has already been suggested. In the case of rotary switches, for example, a lamp has been successfully fixed in the middle of the switch-handle with the lamp adapted to shine through the transparent handle. Other adaptations have likewise been proposed and a number of persons have succeeded in manufacturing various kinds of such switches in the customary dimensions of the ordinary electric switch, with reference both to switches for application to the surface of a wall and for those to be hidden within or by a wall.

With reference to tumbler switches, however, no one has yet succeeded in solving the problem of incorporating a glow lamp, insofar as this inventor knows, as in the usual restricted sizes of these particular switches there is very little space for a lamp in addition to the operating parts of the switch and no satisfactory accommodation for such parts beside the lamp.

The present invention successfully eliminates all the prevailing difficulties and provides a practical tumbler switch with lamp embodiment. This is achieved by fastening the lamp to the switch-base, which is preferably made of press-board, by means of a tubular sleeve-bushing forming at its upper end a bearing for a forked conductor, connecting the junction-contacts with one another or cutting them, as may be required, connecting the said conductor with a similar forked switch handle by an arrangement of spring, and mounting the switch handle to pivot upon an axis positioned parallel to the pivotal axis of the conductor formed as a swing hoop or yoke, and to rest on the base itself.

The invention is illustrated by the attached drawings, in which:

Fig. 1 represents a vertical section through the switch on the plane in which the axis of rotation of the handle and also of the moving contact lies;

Fig. 2 is an alternate section of the switch on a 90° angle to Fig. 1;

Fig. 3 is a top view of the lower part of the switch without the bridge-contact-piece and handle; and

Fig. 4 is a top view of the switch-cap.

In the illustrative construction, the lamp 1, in-

dicating the location of the switch and comprising a so-called dwarf-glowlamp, is fixed into the switch-base 5, preferably made of pressboard, by means of a shell-like socket member or sleeve-bushing 2 made of insulating material and internally threaded to receive the lamp screwed thereto. This socket or bushing 2 is formed in this instance with two opposite laterally disposed wing-lugs or joining-pieces 3, at its lower end, which are turned in behind or under shoulders 10 (see Fig. 2), provided in said base 5, like a bayonet-joint as indicated in dotted lines in Fig. 3. In this position said lugs or joining-pieces bear or rest against an arresting-surface 6 which may advantageously comprise a part of the base, and 15 so hold the bushing firmly in place. The bushing having been inserted in this manner can then be permanently connected with the base 5 as for instance by casting.

At its upper end the aforesigned bushing 2 is 20 formed with two upwardly extending arched portions oppositely disposed at 90 degrees to the lower end jointing lugs. The peaks of these arched portions are reinforced by lateral enlargements 8 outward, and said enlargements constituting two ear-like projections are arcuated or indented upwardly to form downwardly directed cavities. Into these cavities is inserted with correspondingly rounded-off extremities 9 the opposite arms of a U-shaped or hoop-like "swing" 30 contact-piece 10, 11, a side view of which is presented in Fig. 2. Opposite the extremities 9, the arms of said hoop-like contact 10, 11 are provided with bent flaps 12 cooperating with connecting-springs attached to the switch lever and thus 35 effecting the corresponding connections. The upper end of each of said flaps 12 is shaped into an effective hook 13 with which is engaged the suspending end of a helical spring 14 at opposite sides of the socket or bushing member 2. 40

The movable contact piece 10, 11 is given a swing movement to opposite positions by a fork-shaped swing lever or handle 15, to which the upper ends of the aforesigned springs 14 are fixed at 16. The two arms 17 of this fork lever are 45 hollowed out or recessed at the sides facing each other between which the lamp and lamp socket 2 lie, in the manner indicated in Fig. 2, so as the better to receive the springs 14. The ends of the yoke arms 17 are formed with lateral pivot 50 projections 17a which rest in bearing recesses 18 provided in the base and are there held under tension by the springs 14. This forked lever 15 is thus adapted to swing upon an axis within the base parallel to the pivotal or swing axis of the 55

conductor contact 10, 11. It is preferable to provide for said lever axis substantially removed from and below said contact axis, and it is so shown lower in or closer to the bottom of the 5 switch base than said other axis, so as to secure the best result. From the foregoing description and drawings it will be seen that a dead-centre "snap-swing" action is provided by this construction, effectuated by the springs 14 connected between the switch lever and the contact member, 10 whereby said member 10, 11 will be caused to swing instantly to opposite "on and off" positions by operation of the lever. If the lever 15 is swung from the full line position represented in Fig. 2, 15 to the left into the position indicated by dotted lines in said figure, first of all the spring 14 brought within the cavity into the bent position is stretched and then tightened. As soon as the upper end fixed at 16 has advanced far enough 20 to the left, the contact part 10 operated upon through the lower end 12, which thus far has been at rest, will be suddenly pulled around (likewise into the position represented by dotted lines), thereby effecting the switching action. 25 In this switching action, any shock of movement which might otherwise be too great without a cushioning by some well-known arrangement—such for instance as special rubber-buffers—is prevented merely by the U-shaped formation of 30 the recessing in the arms 17 of the switching lever, as well as by the springs 14 themselves, effecting the sudden switching action in a self-cushioned and shockless manner. It is easy to round off the 35 surfaces 20 of the recessing against which the springs lean in one arrested position or the other, in such manner that a cushioning of the shock will be effected over a comparatively long part of the switching or swing movement.

The tumbler switch thus far described is 40 cased by a cap or cover K (see Fig. 4), having a slit S through which the handle-part 24 of the lever fork 15 protrudes. In the present instance, this handle 24 is hollowed out and the entire lever 45 structure of course consists of a light-coloured and transparent material. A crown or hood strip 25 of transparent material, partly globular or partly cylindrical, is further laid supportively upon the shoulders formed by the fork-arms 17 and fits with a central aperture over the part 24. 50 This shrouds or shades the lamp applied in the socket or bushing therebelow. Outwardly said strip bears guidively against ribbed projections 26 formed thereover on the inside of the cap K. When the lamp is lighted and glows in the respective 55 position of connection (especially non-switching of the external circuits of a lighting installation), the strip 25 will shine outwardly through the slit S, thus indicating the location of the switch. For this purpose of course the lamp 60 in its holding socket makes contact with conductor elements connected with the line attachments of the switch so as to allow sufficient current passage through the lamp when the switch is thrown to "off" position, or when the switch is either 65 "off" or "on". The lower end of the lamp is shown resting on a contact 28 which connects with one terminal post of the switch, and its ferrule bears against another contact 29 (see Fig. 3) connecting with the other post of the switch. 70 These opposite terminal posts are conventionally represented in Fig. 3, but it will be understood that they may be variously provided in known ways.

The switch of the illustrative embodiment is designed for use both as a circuit-breaker and as a pole-changing switch, this form being selected to exemplify the invention because it is the one in most general use. As a matter of course, the invention is not in any way bound to this one special type of switch only; and for such reason no further description of the internal structure or arrangements of the contact-springs has been made. It is sufficient to say that the contact 10 piece opens and closes the circuit between the terminal posts with its swing to opposite positions. 5

Having now particularly described and ascertained the nature of my said invention, and in 15 what manner the same is to be performed, I declare that what I claim is:

1. An electric switch including a miniature incandescent glow-lamp for indicating in darkness the location of the switch when the same is 20 thrown to "off" position, comprising in combination, an insulate base, a shell socket fixed centrally in the base and within which the lamp is fitted by screwing, the said shell socket also being an insulate and having its upper part formed into 25 pivot bearings for a swinging contact member, a U-shaped metallic swinging contact-piece having ends engaged in said bearings under spring tension, springs connected on opposite sides to said contact piece, and a forked throw lever to 30 which said springs are also connected, the said lever being pivoted under the spring tension on bearings formed in the base below the pivot axis of said contact-piece and adapted by action of the 35 springs between the two to swing the contact piece with snap action into opposite "on" and "off" positions by throw of the lever in alternate directions.

2. An electric switch according to claim 1 40 wherein the bearings for the ends of the swinging contact-piece comprise inverted cup-shaped cavities formed in upper-end reinforcing enlargements of the shell socket.

3. An electric switch according to claim 1 45 wherein the forked throw lever has recesses formed in the sides of its fork portions facing the lamp socket therebetween and shaped in such manner that in cooperation with the springs connected thereto within said recesses the final movement of the contact piece in switching will 50 be cushioned.

4. An electric switch according to claim 1 55 wherein the throw lever is made of transparent material and its fork-like portions serve to support a separate hooding strip of transparent material providing a shield inside the switch for the lamp while allowing the light therefrom to penetrate outwardly to indicate the position of the switch.

5. An electric switch according to claim 1 60 wherein the throw lever is made of transparent material and its fork-like portions serve to support a separate hooding strip of transparent material providing a shield inside the switch for the lamp while allowing the light therefrom to penetrate outwardly to indicate the position of the switch; the said separate strip of transparent material being arcuated and flush with the inner top surface of a cover applied over the entire structure in unity therewith. 65 70

HERMANN NABAKOWSKI.
